UNITED STATES PATENT OFFICE.

JOSEPH NOWICKI, OF DETROIT, MICHIGAN.

DESIGN FOR AN AQUARIUM.

48,946.

Specification for Design.

Patented Apr. 25, 1916.

Application filed December 8, 1915. Serial No. 65,860. Term of patent 7 years.

To all whom it may concern:

Be it known that I, JOSEPH NOWICKI, a subject of the Czar of Russia, residing at Detroit, in the county of Wayne and State of Michigan, have invented a new, original, and ornamental Design for an Aquarium, of which the following is a specification, reference being had to the accompanying drawing, forming part thereof.

The figure is a view in front elevation of an aquarium, showing my new design.

I claim:—

The ornamental design for an aquarium, as shown.

J. NOWICKI.

Witnesses:

ALEXANDER TCKSERCSIN,

JOHN B. RUDCK.
